Primary Examiner — Messina L Smith*Assistant Examiner* — Elizabeth Borsetti(74) *Attorney, Agent, or Firm* — Lippes Mathias LLP(57) **CLAIM**

The ornamental design for a card with separable applicators, as shown and described.

DESCRIPTION

FIG. 1. is a perspective view of a card with separable applicators showing my new design;
 FIG. 2 is a front plan view thereof;

FIG. 3 is a first side plan view thereof;

FIG. 4 is a the other side plan view thereof;

FIG. 5 is a top end view thereof;

FIG. 6 is a bottom end view thereof;

FIG. 7 is a rear plan view thereof; and,

FIG. 8 is a perspective view of the card with separable applicators shown in an environment of use with a single applicator separated from the card.

The broken line showing of the hand in FIG. 8 illustrates environment and forms no part of the claimed design. All other broken lines illustrate portions of the card with separable applicators that form no part of the claimed design.

1 Claim, 4 Drawing Sheets(56)
